United States Patent Office

Des. 229,241

Patented Nov. 13, 1973

229,241

TENT

Harold J. Pohl, Washington, Mo., assignor to Kellwood Company, St. Louis, Mo.

Filed July 17, 1972, Ser. No. 272,289

Term of patent 7 years

Int. Cl. D21—04

U.S. Cl. D88—3 B

FIG.1

FIG. 5

FIG. 1 is a perspective of a tent showing my new design;
FIG. 2 is a front elevational view thereof;
FIG. 3 is a side elevational view thereof, the opposite side being identical thereto;
FIG. 4 is a top plan view thereof;
FIG. 5 is a rear elevational view thereof.
I claim:
The ornamental design for a tent, substantially as shown and described.
